COMBINED JUG AND DUCK DECOY

Gordon L. Fahlgren, Crockett, Calif., assignor of one-half
to Vern C. Fahlgren, Klamath Falls, Oreg.

Filed Dec. 28, 1964, Ser. No. 83,190

Term of patent 14 years

(Cl. D58—5)

FIGURE 1 is a side elevational view of a combined jug and duck decoy embodying my new design;

FIGURE 2 is a front elevational view;

FIGURE 3 is a top plan view;

FIGURE 4 is an elevational view with the duck head portion in a different position;

FIGURE 5 is a top plan view of FIG. 4; and

FIGURE 6 is an elevational view looking from the left of FIG. 4.

I claim:

The ornamental design for a combined jug and duck decoy, substantially as shown.
